UNITED STATES PATENT OFFICE

WILLIAM O. WELLS, OF MINNEAPOLIS, MINNESOTA, ASSIGNOR TO WELLS-LAMONT MANUFACTURING COMPANY, OF MINNEAPOLIS, MINNESOTA, A CORPORATION OF MINNESOTA

GLOVE

Application filed April 26, 1930. Serial No. 447,566.

This invention relates to new and useful improvements in gloves, particularly working men's gloves of the type having the palm and finger portions constructed of leather, 5 and the back and wrist portions of a suitable cloth or fabric.

An object of the invention is to provide such a glove including a portion adapted to cover the palm of the hand and forming the

10 fronts of two of the fingers, another portion forming the back of the glove and stitched at its sides to said palm portion, the forward edge of said back portion being curved inwardly from both sides and in a direction 15 towards the fingers and terminating at a point substantially at the juncture of the two middle fingers; a portion shaped to form the backs of the first and second fingers and another portion forming the backs of the 20 third and fourth fingers, said back finger portions being suitably stitched to the front finger portions, and the back finger portions having their rear edges curved to correspond to the forward curved edge portions of said 25 back portion and suitably stitched thereto.

A more specific object is to provide a glove comprising a leather portion adapted to cover the palm of the hand and two of the fingers, a leather portion forming the fronts of the 30 two middle fingers; a cloth portion forming the back of the glove and stitched at its sides to said palm portion, the forward edge of said back portion being curved inwardly from both sides and in a direction towards 35 the fingers and terminating at a point substantially at the juncture of the two middle fingers; a leather portion shaped to form the backs of the first and second fingers, and another leather portion forming the backs of the 40 third and fourth fingers, said back finger portions being suitably stitched to the front finger portions, and the back finger portions having their rear edges curved to correspond to the curved edge portions of said back cloth 45 portion and suitably stitched thereto.

A further object is to provide a glove constructed in such a manner as to provide the utmost in wear and, at the same time, one which will be comfortable to the user, the back of the glove being constructed of a soft

pliable material such as cloth and the palm and fingers being constructed of leather and the backs of the fingers being formed of two separate parts united by curved rows of stitches to the back portion of the glove, 55 thereby providing a glove which will be extremely flexible at the knuckles and, at the same time, one which will withstand considerable wear and rough usage.

A further object is to provide an improved 60 working glove which may be made from small pieces of material and will be simple and economical to manufacture.

Other objects of the invention will appear 65 from the following description and accompanying drawings and will be pointed out in the annexed claims.

In the accompanying drawings, there has been disclosed a structure designed to carry out the various objects of the invention, but 70 it is to be understood that the invention is not confined to the exact features shown as various changes may be made within the scope of the claims which follow.

In the drawings:

Figure 1 is a back view of my improved 75 glove showing the manner of uniting the back finger portions with the back portion of the glove;

Figure 2 is a view showing the shapes of 80 the back finger portions and the back of the hand portion, said parts being shown slightly separated from one another; and

Figure 3 is a front view of the completed 85 glove.

The novel glove featured in this invention comprises a front or palm portion 2 adapted to cover the palm of the hand and having integral portions 3 and 4 shaped to form the fronts of the first and fourth fingers, as shown 90 in Figure 3. The thumb 5 is secured to the palm portion 2 in the usual manner. The fronts of the middle fingers of the glove are formed from an integral portion 6 having narrow portions 7 and 8 shaped to form the 95 fronts of these two fingers, as shown.

A feature of this invention resides in the construction of the back of the glove, which is such as to provide a glove which will be very flexible at the knuckles and, at the same 100

time, one which will be strong and durable. As shown in Figures 1 and 3, the back of the glove comprises a back portion 9, preferably made from a suitable cloth or fabric, and the finger portions 11 and 12, preferably of leather. The back portion 9 is suitably stitched at its side edges to the palm portion 2.

The finger portion 11 forms the backs of the first and second fingers and the portion 12 the backs of the third and fourth fingers. The forward edge portions 15 and 16 of the back portion 9 are curved inwardly from both sides and in a direction towards the fingers and terminate in a point 17, situated substantially at the juncture of the two middle fingers, as clearly shown in Figures 1 and 2.

The back edges 18 and 19 of the finger portions 11 and 12, respectively, are correspondingly curved, and are secured to the edge portions 15 and 16 of the back portion 9 by suitable rows of stitches 21, shown in Figure 1.

By thus constructing the back of the glove, it will be very flexible at the knuckles of the hand so as to permit free movement of the fingers and thus eliminate the stiffness often found in gloves having the back finger portions stitched to the back portion of the glove, a straight row of stitches extending across the back of the glove.

In the drawings, I have shown the glove provided with a gauntlet 22 suitably stitched to the palm and back portions 2 and 9, respectively, by suitable stitches 23. The gauntlet is preferably constructed of a comparatively stiff material and the front portion or side thereof is reinforced by means of a member 24, preferably of leather, suitably stitched to the glove, as clearly shown in Figure 3.

By making the backs of the fingers of two separate parts, as best shown in Figure 2, these parts may be made from small pieces of leather which might otherwise have to be scrapped, thereby economizing on material, with a resultant lowering in the cost of manufacture.

I claim as my invention:

1. A glove including a portion adapted to cover the palm of the hand, portions forming the fronts of the fingers, another portion forming the back of the glove and stitched at its sides to said palm portion, the forward edge of said back portion being curved inwardly and forwardly from both sides and terminating in a point situated substantially between the two middle fingers, a portion shaped to form the backs of the first and second fingers and another portion forming the backs of the third and fourth fingers, said back finger portions being suitably stitched to the front finger portions, and said back finger portions having their rear edges shaped to correspond to the curved edge por-

tions of said back portion and suitably stitched thereto.

2. A glove comprising a front portion of leather adapted to cover the palm of the hand and two of the fingers, a leather portion forming the fronts of the two middle fingers, a cloth portion forming the back of the glove and stitched at its sides to said front portion, the front edge of said back portion being curved inwardly and forwardly from both sides and terminating in a point situated substantially between the two middle fingers, a portion shaped to form the backs of the first and second fingers and another portion forming the backs of the third and fourth fingers, said back finger portions being of leather and suitably stitched to said front finger portions, and said back finger portions having their rear edges shaped to correspond to the curved edge portions of said back portion and suitably stitched thereto.

In witness whereof, I have hereunto set my hand this 19th day of April, 1930.

WILLIAM O. WELLS.
